[57] ABSTRACT

Acenaphthene derivatives are provided having the general structure:

wherein R and R' are alkyl having from one to about three carbon atoms. These compounds possess anti-inflammatory activity.

4 Claims, No Drawings

ACENAPHTHENE DERIVATIVES

The present invention relates to acenaphthene derivatives and more particularly to acenaphthenequinone dialkoximes having anti-inflammatory activity as well as cardiovascular and central nervous system activity and sunscreening properties.

The compounds of this invention are useful as anti-inflammatory agents and are effective in the prevention and inhibition of granuloma tissue formation in warm-blooded animals, for example, in a manner similar to indomethacin. They may be used to decrease joint swelling tenderness, pain and stiffness, in mammalian species, e.g., in conditions such as rheumatoid arthritis. A compound of Formula I (below) may be compounded according to accepted pharmaceutical practice in oral dosage forms such as tablets, capsules, elixirs or powders for administration of about 100 mg. to 2 gm. per day, preferably 100 mg. to 1 gm. per day in two to four divided doses.

The acenaphthenequinone derivatives of the invention have 20 the general formula:

wherein R and R' can be the same or different and are alkyl having from one to three carbon atoms, such as methyl, ethyl, propyl or isopropyl.

Exemplary of the compounds falling with the present invention are the acenaphthenequinone dimethoximes, acenaphthenequinone diethoximes, acenaphthenequinone diisopropoximes, 1-methoximino-2-ethoxyacenaphthenequinone and 1-methoximino-2-propoxyacenaphthenequinone.

The compounds of the invention can be prepared by reacting acenaphthenequinone with an excess of alkoxyamine hydrohalide and a base in the presence of a solvent for the reactants.

The base can be an organic base or an inorganic base such as pyridine, sodium acetate, potassium acetate, sodium hydroxide, potassium hydroxide or cesium hydroxide. Pyridine is preferred inasmuch as it serves as both a base and a solvent.

In addition to pyridine, the solvent can be an alcohol containing up to about four carbon atoms, such as methyl alcohol, ethyl alcohol, propyl alcohol, isopropyl alcohol, n-butyl alcohol, sec. butyl alcohol or tert. butyl alcohol. Dimethyl sulfoxide may also be employed as a solvent.

The alkoxyamine hydrohalide can be methoxyamine hydrochloride, ethoxyamine hydrochloride, n-propoxyamine hydrochloride, isopropoxyamine hydrochloride, methoxyamine hydrobromide, ethoxyamine hydrobromide, n-propoxyamine hydrobromide or isopropoxyamine hydrobromide.

In carrying out the above reaction, the alkoxyamine hydrohalide should be employed in a weight ratio to the acenaphthenequinone (alkoxyamine hydrohalide:acenaphthenequinone) within the range of from about 1:1 to about 10:1 and preferably from about 1:1 to about 4:1.

The reaction of the acenaphthenequinone and alkoxyamine hydrohalide can be carried out at room temperature. However, if desired, higher temperatures, ranging from about 25° to about 100° C. and preferably from about 25° to about 50° C. may be employed to expedite reaction. Temperatures higher than 100° C. can be employed, however, with no apparent benefit.

The compounds of the invention may be in the form of one or more geometric isomers, one symmetrical form and one unsymmetrical form, which can be depicted as follows:

Thus, for example, acenaphthenequinone dimethoxime can have the following structures:

and

The various geometric isomers can be separated from mixtures thereof by conventional thin layer and vapor phase chromatographic procedures.

The following examples in the opinion of 1 inventor represent preferred embodiments of his invention:

Example 1

Acenaphthenequinone Dimethoximes

A mixture of 5 g. of acenaphthenequinone and 5 g. of methoxyamine hydrochloride in 100 ml. of pyridine is warmed to achieve solution and then allowed to stand at room temperature overnight. The mixture is poured into water, and the resulting precipitate is collected by filtration. A chloroform solution of the solid is washed with 2N hydrochloric acid, 8 percent salt solution, dried (Na_2SO_4) and evaporated. The residue is crystallized from isopropyl ether-hexane to give a mixture of acenaphthenequinone dimethoximes, 4.1 g., m.p. 124°-130°. The mixture is separated by plate chromatography on silica gel using chloroform-hexane (1:1) as the developing solvent. Crystallization of the less polar product from isopropyl ether gives a symmetrical acenaphthenequinone dimethoxime, m.p. 146.5°-147.5°; $\tau_{\text{CDCl}_3}^{\text{TMS}}$ 5.70 (s, = NOCH_3), 1.73 (q, 7.13, 0.91 cps, ortho-H).

Anal. Calc'd for $\text{C}_{14}\text{H}_{12}\text{N}_2\text{O}_2$: C, 69.99; H, 5.03;

N, 11.66.

60 Found: C, 69.70; H, 5.06;

N, 11.60.

Crystallization of the more polar product from isopropyl ether gives unsymmetrical acenaphthenequinone dimethoxime, m.p. 153°-153.5°. Recrystallization from isopropyl ether gives the analytical sample, m.p. 153°-153.5°; $\tau_{\text{CDCl}_3}^{\text{TMS}}$ 5.74, 5.68 (s, = NOCH_3), 2.19 (q, 5.94, 0.53 cps, ortho-H), 1.74 (q, 6.57, 0.72 cps, ortho-H).

Anal. Calc'd for $\text{C}_{14}\text{H}_{12}\text{N}_2\text{O}_2$: C, 69.99; H, 5.03;

N, 11.66.

70 Found: C, 70.13; H, 5.06;

N, 11.67.

Example 2

Acenaphthenequinone Diethoximes

In a manner similar to that described in Example 1, but substituting ethoxyamine hydrochloride for methoxyamine hydrochloride, a mixture of isomers of the title compound is obtained.

Example 3

1-Methoximino-2-ethoximinoacenaphthenequinone

A mixture of 1.0 g. of acenaphthenequinone and 458 mg. of methoxyamine hydrochloride in 20 ml. of pyridine is stirred at room temperature overnight. The mixture is poured into water and the resulting precipitate collected by filtration to give 0.82 g. of acenaphthenequinone monomethoxime.

A mixture of 0.82 g. of acenaphthenequinone monomethoxime and 600 mg. of ethoxyamine hydrochloride in 20 ml. of pyridine is stirred at room temperature overnight. The mixture is poured into water and the resulting precipitate collected by filtration to give the title compound.

What is claimed is:

1. An acenaphthene derivative having the structural formula selected from the group consisting of

wherein R and R' are the same and are alkyl having from one to three carbon atoms.

2. An acenaphthene derivative in accordance with claim 1 having the structural formula:

10 3. Isomers of acenaphthene derivatives in accordance with claim 1 having the structural formula:

4. An acenaphthene derivative in accordance with claim 1 wherein R and R' are ethyl.

UNITED STATES PATENT OFFICE
CERTIFICATE OF CORRECTION

QA26

Patent No. 3,679,747 Dated July 25, 1972

Inventor(s) Seymour D. Levine

It is certified that error appears in the above-identified patent and that said Letters Patent are hereby corrected as shown below:

Column 1, line 59, "n-propax-" should read --n-propox- --.

Column 1, line 71, "higher than 1002 C." should read --higher than 100°C.--.

Column 2, line 38, "in the opinion of 1 inventor" should read --in the opinion of the inventor--.

Signed and sealed this 1st day of May 1973.
